(57) **CLAIM**

The ornamental design for a golf club stand, as shown and described.

DESCRIPTION

FIG. 1 is a top front right perspective view of a golf club stand showing our new design as might be used holding a putter golf club.

FIG. 2 is a top rear right perspective view thereof.

FIG. 3 is a rear view thereof.

FIG. 4 is a top view thereof.

FIG. 5 is a front view thereof.

FIG. 6 is a bottom view thereof.

FIG. 7 is a left side view thereof; and,

FIG. 8 is a right view thereof.

The broken lines shown are included for the purpose of illustrating environment and form no part of the claimed design.
